UNITED STATES PATENT OFFICE.

MARVIN H. JESTER, OF DENVER, COLORADO, ASSIGNOR TO THE M. H. JESTER INVESTMENT COMPANY, A CORPORATION OF COLORADO.

MEANS FOR SUPPORTING PLASTER-BOARDS IN PARTITION CONSTRUCTION.

1,078,144.

Specification of Letters Patent. Patented Nov. 11, 1913.

Application filed October 14, 1912. Serial No. 725,709.

To all whom it may concern:

Be it known that I, MARVIN H. JESTER, a citizen of the United States of America, residing in the city and county of Denver and 5 State of Colorado, have invented a new and useful Means for Supporting Plaster-Boards in Partition Construction, of which the following is a specification.

My invention relates to improvements in 10 means for supporting plaster boards, used in partition construction.

The object of the invention is to provide in connection with a channel bar form of studding, a plurality of clips comprising 15 substantially U-shaped metal plates which are divided through their horizontal base members and through one of their upright members so as to straddle a channel bar or stud in such manner as to engage the channel 20 bar with its undivided side or upright member, while its opposite divided member is sprung over the edge of a plaster board to clamp the same to the channel bar in cases of single partitions; clips of the same design 25 but of greater length being used to clamp plaster boards to opposite sides of the channel bars in forming double partitions. This object is accomplished by the support illustrated in the accompanying drawings, in 30 which:

Figure 1 is a front view of a portion of a partition showing plaster boards supported by my improved supporting means. Fig. 2 is a horizontal sectional view of a portion 35 of a partition—full size—on the line 2—2 of Fig. 1. Fig. 3 is a vertical sectional view of a portion of the partition on the line 3—3 of Fig. 2. Fig. 4 is a perspective view of 40 one of the clips in engagement with a portion of a plaster board, the stud or channel bar being shown in proper relative position, in dotted lines. Fig. 5 is an edge view of one of the clips, showing the ends or upright members bent slightly toward each other, 45 said ends being sprung when the clip is applied. Fig. 6 is an end view of the clip showing the divided member. Fig. 7 is a perspective view showing a channel bar and a clip of the length required in forming a 50 double portion, two sets of plaster boards and a companion clip being shown in dotted lines. Fig. 8 is a vertical sectional view of a portion of a double partition. Fig. 9 is a horizontal sectional view thereof. Fig. 10 55 is a perspective view of a modification in

which a single clip is arranged to perform the function of two clips, and Fig. 11 is a view of the blank from which the clip 10 is formed.

Referring to the accompanying drawings: 60 The numeral 1 indicates the studs or uprights, which are preferably metal channel bars of suitable dimensions, those illustrated being three-fourths of an inch wide by three-eighths of an inch deep and of a length to 65 extend from floor to ceiling, to which their respective ends are firmly secured.

In Figs. 1 to 4 I have illustrated a single partition, or one in which a single thickness of plaster boards is employed. In this arrangement the boards are placed against one side only of the channel bar, and their meeting ends or joints are preferably arranged in staggered form, or so that those of each alternate row of boards are in the same vertical line, as clearly shown in Fig. 1, this arrangement preventing the formation of cracks along the length of the studs after 75 the plaster has set.

The plaster boards 2 are placed against 80 the channel bars in horizontal rows, one row above another, and are clamped to said bars by clips 3, which are formed as follows: Metal plates of suitable dimensions are employed, and the end portions of each plate 85 are bent at right angles to its base or main portion, the space between the two bent ends corresponding to the width of a channel bar and the thickness of a plaster board, when the clips are used for single partitions; but 90 when used for a double partition, as shown by Figs. 7 to 9, the space between the bent ends is the equivalent of the width of a channel bar and two thicknesses of plaster board, as will be understood. Before the ends of 95 the plate are bent, however, a longitudinal strip of metal, equal in width to the depth of the channel bar, is cut or stamped out of it, leaving a central slot or space 4, which extends from one end of the plate to the 100 point where the bend would occur adjacent to the opposite end of the plate. The ends of the plate are then bent at right angles to its base, as clearly shown by Fig. 4, to form a substantially U-shaped clip, the base and one 105 end of which is centrally divided or slotted. The clips are placed upon the channel bars so as to straddle them, as shown, the bar extending through the slot 4, and the solid or undivided end 5 of the clip bearing 110

against one of the sides of the said channel bar. The divided end 6 of the clip is then in position to extend over the upper or lower horizontal edge of a plaster board and engage its face, as will appear by reference to Fig. 4.

In practice, the plaster boards are placed one above another against the channel bars, in the manner shown by Fig. 1, each board 10 being secured before the next board is placed in position. Beginning with a bottom board, clips are first placed upon the two channel bars, to which the board is to be secured, with their ends extending upward, 15 and before placing the clips, their ends are pressed by the operative so as to incline slightly toward each other, as shown in Fig. 5. The lower edge of a plaster board is then inserted between the upturned, divided ends 20 6 of the clips, and the adjacent sides of the channel bars, and as the space between the ends of the clips, before they are pressed, corresponds to the width of a channel bar and the thickness of a plaster board, it will 25 be seen that the edge of the plaster board must be forced in between the end of the clips and the channel bars, and this springing of the ends of the clips will cause them to firmly grip or engage the sides of the 30 channel bars and the surface of the plaster boards, so that the said boards will be firmly held in contact with the bars. Clips are next placed upon the bars so as to rest upon the clips, which engage the upper edge of the 35 board, their ends extending upward, so as to engage the lower edge of the next board, as shown by Fig. 1, and thus the boards are secured until they extend from floor to ceiling, the ends of the boards in each alternate 40 row being in the same vertical line, in order to break the joint along the channel bar, as before mentioned.

In Figs. 7 to 9 I have shown a double partition, or one in which plaster boards are 45 secured to both sides of the channel bars. The clip 7 used in the double partition, is identical with that used in the single partition, excepting as to length, the clip 7 being long enough to clamp boards on opposite 50 sides of the bars, as shown.

In Figs. 10 and 11 is illustrated a twin or double clip, 8, which is adapted to take the place of two such clips as are shown in the other views. This clip is made from a plate 55 of suitable dimensions, which is also slotted or divided as shown at 9, so as to straddle the channel bars in like manner as the clips 3 and 7. To form the board-engaging members of this clip, its opposite end portions 60 are each formed with two parallel slits 10, which extend from the edges of the plate to the points 11, where the right angle bends are formed. The slits on each side of the

plate are in line, and are midway between the edges of the slot 9 and the side edges of 65 the plate. The slits at one end of the plate or blank form outer fingers 12 and inner fingers 13, the inner fingers being bent at right angles to the plate in one direction, while the outer fingers 12 are bent at right 70 angles to the plate and in the opposite direction to the fingers 13. The slits at the opposite end of the blank form outer fingers 14, which are bent at right angles to the plate, and in the same direction as the fingers 13, 75 while the portion 15 between, is bent at right angles and in the opposite direction to the fingers 14. In practice, these clips are placed astride the channel bars in like manner as the clips 3 and 7, their base or main 80 portions lying between the horizontal edges of two boards, and their fingers clamping to the boards against the sides of the channel bars, as will be understood. This clip may be used either for single or double partitions. 85 After the plaster boards have been secured to the studding, the usual rough and finishing coats of plaster are applied to opposite sides of the boards, as shown by dotted lines, Fig. 2.

The clip herein described is not only extremely simple and thoroughly practical, but it eliminates the key or wedge necessary in clips for plaster boards in present use.

While I have illustrated the clip in connection with partition construction, it should be understood that it is equally well adapted for ceiling construction also.

Having described my invention, what I 100 claim as new and desire to secure by Letters Patent, is:

1. In a supporting device for plasterboards, a stud, and a clamping-plate comprising a horizontal portion and right-angle 105 end portions adapted to secure plasterboards to said stud, said horizontal portion and one of said end portions being slotted to permit said clamping-plate to straddle the stud.

2. In a supporting device for plasterboards, a stud, and a clamping-plate comprising a horizontal portion and right-angle 115 end portions divided and bent to form oppositely projecting fingers adapted to secure the plaster-boards to said stud, said horizontal portion and one of said end portions being slotted to permit said clamping-plate to straddle the stud.

In testimony whereof I affix my signature 120 in presence of two witnesses.

MARVIN H. JESTER.
